(57) **CLAIM**

The ornamental design for a beverage bottle, as shown and described.

DESCRIPTION

FIG. 1 is a perspective view of the beverage bottle.

FIG. 2 is a front elevation view of the beverage bottle.

FIG. 3 is a rear elevation view of the beverage bottle.

FIG. 4 is a right side elevation view of the beverage bottle. A left side elevation view is a mirror image of the right side elevation view of the beverage bottle.

FIG. 5 is a top plan view of the beverage bottle.

FIG. 6 is a bottom plan view of the beverage bottle; and, FIG. 7 is another perspective view thereof with the lid of the beverage bottle shown in an open position.

The broken lines showing in the figures are included for the purpose of illustrating portions of the beverage bottle that form no part of the claimed design.

1 Claim, 7 Drawing Sheets
